FIG. 6.

Figure 1 is a front elevational view of a bowler's hand towel, embodying my new design;

Fig. 3 is a rear elevational view;

Fig. 4 is a front elevational view, with the hook element omitted for convenience of illustration;

Fig. 5 is a top plan view; and

The characteristic feature of the design resides in the elongated tubular towel having pleated edges and a contrasting border suggestive of the gutters of a bowling alley in combination with a representation of an oversized bowling pin at the lower end and a rounded button suggestive of a bowling ball at the upper end, all as shown.
